UNITED STATES PATENT OFFICE

JOHN J. RITTER, OF URBANA, OHIO, ASSIGNOR TO THE W. B. MARVIN MANUFACTURING COMPANY, OF URBANA, OHIO, A CORPORATION OF OHIO

WINDOW SCREEN

Application filed November 7, 1932. Serial No. 641,516.

This invention relates to improvements in adjustable window screens, it more particularly relating to the means for slidably connecting the screen sections.

Adjustable window screens are usually composed of two sections of similar but reversed hand construction, and are assembled so each section has a sliding movement with each other whereby the length of the screen may be varied. The section elements sometimes known as rails are usually provided with mating grooves, and the members which connect the sections to each other must, on the one hand, be capable of being securely fastened in the groove of one rail, and on the other hand, must also be capable of sliding freely in the corresponding groove of the other rail.

In many of the earlier screens, the connecting members required one or more operations to fix them securely in place, and in addition fastenings such as nails were required. Members of one type hold themselves firmly in place and resist a movement tending to dislodge them when a force is applied in one direction, but were easily moved when a force was applied in the opposite direction. In practically all cases where the screen sections were made of wood, the firmness of the anchoring depended on the weather conditions, the members becoming loose in dry weather.

The object of the present invention is the provision of an inexpensive and durable connecting member of the class described, whose gripping effect is not diminished by changes in weather conditions, and for insertion of which no tools are necessary, and one which will resist ordinary forces tending to dislodge the same acting in either direction.

Other objects and advantages will appear in the following specifications and claims.

In the accompanying drawing:

Fig. 1 is a perspective view of a portion 45 of an adjustable screen having incorporated therein the improved connecting members.

Fig. 2 is an enlarged fragmentary transverse section taken on the line 2—2 of Fig. 1.

Fig. 3 is also an enlarged fragmentary 50 transverse section on the line 3—3 of Fig. 1.

Fig. 4 is a side elevation of one of the improved members, the scale of the view being approximately twice the size of the member.

Figs. 5 and 6 are transverse sections on the lines 5—5 and 6—6 respectively. 55

Fig. 7 is a bottom plan of the improved member on the same scale as Fig. 4, the view also showing the outline of the blank from which the member is formed.

Fig. 8 is a perspective view of the improved 60 member enlarged to twice the size thereof.

Referring to Fig. 1 of the drawing, it will be understood that the portion of the screen not shown corresponds exactly to the portion which is shown. The screen sections are composed of the section 1 on the left hand and the section 2 on the right hand. Each section consists of an end piece 3 and 4, and an upper longitudinal rail 5 and 6, respectively, the lower rails not being shown. As is usual in 70 such screens the construction of each section is identical except for the necessary complementary formation whereby a completed adjustable screen is produced.

The reference character 8 refers to the 75 screen material, which may be of any suitable material, such as wirecloth, fabric or as is employed in the present invention, portions of thin flat sheet metal slotted and formed to provide louvres (not shown). 80

Each rail 5 and 6 is provided with a longitudinally extending groove 9 which grooves face each other in the assembled screen. Each groove 9 is angularly undercut at the top and bottom as best seen in the extreme 85 right hand portion of Fig. 1. When the rails are placed together as in assembly, the grooves appear as seen in Figs. 2 and 3.

The connecting member, which will be known as the clip, is designated at 10. It is 90 formed in one piece from flat, sheet metal having spring temper characteristics, the broken lines in Fig. 7 showing the outline of the blank. The blank is formed by subsequent operations to a substantially U-shaped 95 cross-section (Figs. 4 and 5), having a flat connecting portion 12 and legs 14 which are out-turned at their face edges to form flanges 17. The clip is so constructed that one part thereof has free sliding contact with the walls 100

of the groove in one section, while the other part is anchored against movement, in the groove of the other section. The spacing apart of the legs of the clip is necessarily dependent on the space between the lips of the groove, and to allow insertion of the clip therein and to firmly anchor the clip in the groove, and connecting portion 12 is widened at the center thereof by wings 13. The material for the wings 13 is taken from the portion of the blank which later forms the legs 14 of the clip, and when the legs are bent to position, the wings are left extending from each edge of the connecting portion and thereby have the benefit of the strength of the connecting portion of the clip.

When a clip is inserted in a groove, the clip makes contact with the walls of the groove through the wings, the wings engaging the groove in the sharp corners 9'. To provide a further insurance for a firm anchorage, the wings are subjected to another operation consisting of bending each wing at the central portion thereof transversely of the longitudinal extension of the clip as best seen in Figs. 4 and 6. This bending operation provides for imparting to the wing a bowed form, the center of which is shown at 15 (Figs. 4 and 8), and although not essential, this bending operation is shown as including the connecting portion 12.

The gripping action is further enhanced by forming the corners of the wings as best seen in Fig. 7, the angular corners 16 imbedding themselves in the flat vertical side of the groove 9. The angular nature of the corners also provide a resistance against movement of the clip in either direction, since each corner points in an opposite direction.

The remaining portion of the clip comprising the legs 14 and the outturned flanges 17 is formed to such dimensions as will permit a free sliding movement in the groove 9 of the mating rail as shown in Figs. 2 and 3, the flanges 17 engaging the angularly disposed sides 18 of the groove. To minimize any tendency of the legs 14 to bend inwardly, a portion 19 at each end of the part 12 is slotted back and turned inwardly between the legs 14, where these portions act as spacers.

To assemble the sections into a screen, a clip is placed in each groove at the open end thereof, with its sliding portion (the legs 14 and flanges 17) inserted in the groove, and is then slid to the opposite end of the groove adjacent the end pieces 3 and 4. The sections are then placed in position and each clip is slid back and forced into the open end of the mating groove to the depth desired.

From the foregoing specification it will be seen that there is thus provided an improved connecting member which is inexpensive to make and install, no tools being required, and

whose gripping effect in the groove in which the clip is inserted is not lessened by adverse weather changes, since if the rail becomes dry and undergoes a fibre change, the spring characteristics of the wings causes these latter portions to follow the material in its changes.

Having thus described my invention, I claim:

1. In an adjustable window screen having slideable sections with mating undercut grooves, a metallic clip substantially U-shaped in cross-section to form a pair of legs and an intermediate connecting portion, and wings struck from the leg portions of the clip and projecting in line with the connecting portion thereof for anchored engagement with the walls of the groove of one section, the legs of the clip being formed to slidably engage with the walls of the groove of the other section.

2. In an adjustable window screen having slideable sections with mating undercut grooves, a metallic clip substantially U-shaped in cross-section to form a pair of legs and an intermediate connecting portion, and wings struck from the leg portions of the clip and projecting in line with the connecting portion thereof for anchored engagement with the walls of the groove of one section, the free end of each leg being bent at an angle thereto to adapt the legs for slideable engagement with the walls of the groove of the other section.

3. In an adjusting window screen having slideable sections with mating undercut grooves, a metallic clip substantially U-shaped in cross-section to form a pair of legs and an intermediate connecting portion, wings struck from the leg portion of the clip and projecting in line with the connecting portion thereof for anchored engagement with the walls of the groove of one section, each of said wings being bent to a substantial bow shape, the legs of the clip being formed to slidably engage with the walls of the groove of the other section.

4. In an adjustable window screen having slideable sections with mating undercut grooves, a metallic clip substantially U-shaped in cross section to form a pair of legs, and an intermediate connecting portion, oppositely extending wings struck from the leg portions of the clip and projecting in line with the connecting portion thereof, the side edges of each of said wings being converged toward the connecting portion to provide outer pointed corners thereon, and each of said wings being bent to a substantially bow shape, said wings being adapted for anchored engagement with the walls of the groove of one section, the legs of the clip being formed to slidably engage with the walls of the groove of the other section.

5. In an adjustable window screen having slideable sections with mating undercut

grooves, a metallic clip substantially **U**-shaped in cross-section to form a pair of legs and an intermediate connecting portion, each end of the intermediate connecting portion being bent to lie between said legs and act as a spacer therefor, and wings struck from the leg portions of the clip and projecting in line with the connecting portions thereof for anchored engagement with the walls of the groove of one section, each of said wings being formed with pointed outer corners and of a slightly bow shape, each of the legs of the clip having its free end bent at an angle thereto to slidably engage with the walls of the groove of the other section.

In testimony whereof, I have hereunto set my hand this 2nd day of November 1932.

JOHN J. RITTER.
